G. L. WILLITS,
COOLING DEVICE FOR INTERNAL COMBUSTION ENGINES,
APPLICATION FILED MAY 31, 1918.

1,299,889.

Patented Apr. 8, 1919.

UNITED STATES PATENT OFFICE.

GUY L. WILLITS, OF MINNEAPOLIS, MINNESOTA.

COOLING DEVICE FOR INTERNAL-COMBUSTION ENGINES.

1,299,889.

Specification of Letters Patent. Patented Apr. 8, 1919.

Application filed May 31, 1918. Serial No. 237,447.

To all whom it may concern:

Be it known that I, GUY L. WILLITS, a citizen of the United States, residing at Minneapolis, in the county of Hennepin and 5 State of Minnesota, have invented certain new and useful Improvements in Cooling Devices for Internal-Combustion Engines, of which the following is a specification.

My invention relates to cooling devices for 10 internal combustion engines and the object is to provide a device which will insure an efficient circulation of water from the engine to the radiator and back to the engine.

A further object is to provide a gear pump 15 for causing the circulation of water and to operate a fan at a high rate of speed in connection with the pump. A further object is to provide a pivotally mounted pump casing which may be readily adjusted to 20 take up slack in a flexible driving connection for operating the pump without at the same time removing the fan from its effective sphere of action relatively to the engine.

The full objects and advantages of my invention will appear in connection with the 25 detailed description and are particularly pointed out in the claims. Referring to the drawings which show the application of my invention in one form,—

30 Figure 1 is a view in side elevation of the device applied to an internal combustion engine. Fig. 2 is a view on line 2—2 of Fig. 1. Fig. 3 is a view in transverse section through the pump casing. Fig. 4 is a top 35 plan view with the pump casing partly broken away.

In the drawings 10 designates the customary radiator and 12 the engine casing of an internal combustion engine, the two being 40 connected at the top by pipe 14 in the usual way. The pipe 16 at the bottom of the radiator instead of leading directly to the engine, as usual, leads to the top of a pump casing 18, while from the bottom of this 45 casing a pipe 20 leads to the engine. A bracket 22 is secured to the engine by bolts 24 and the upper end of the bracket is turned forwardly and forked to provide the two branches 26. The pump casing is pivotally 50 attached to the bracket by means of a laterally extending lug 28 thereon which fits between the branches 26 of the fork, while a bolt 30 passing through holes in the end of the lug and the two branches serves as a 55 pivot. The pump casing is held in adjustable position by means of a lug 32 thereon

having an opening 33 through which passes a bolt 34 provided with lock nuts 36 on each side of the lug whereby the position of the pump casing may be adjusted. The pump 60 casing is provided with the removable cover portion 38 held thereon by bolts 40 screw threaded into holes 42 in the adjacent edge of the casing. Within the pump chamber 44 are two intermeshing gears 46 and 48, the 65 latter being considerably smaller than the former. The gear 46 is secured to a shaft 50 mounted in bearings on the casing, the shaft passing through a stuffing box 52. The shaft 50 may be driven in any suitable manner 70 from the engine as by means of the customary fan belt either straight or crossed according to whether the fan is run clock-wise or counterclock-wise. However, on account of the liability of slipping of a belt, I prefer 75 to use the following driving means: Secured on the outer end of the shaft 50 is a sprocket wheel 54 over which passes a sprocket chain 56 which also passes over a sprocket wheel 58 secured to the engine crank shaft 60 80 which may be provided with the customary crank handle 62. Sprocket wheels 54 and 58 are preferably of the same size. The smaller gear 48 is secured to a shaft 64 85 mounted in bearings on the pump casing and passing through a stuffing box 66. To the forward end of the shaft 64 in proximity to the radiator is secured a fan 68. The two gears 46 and 48 are designed to fit snugly in 90 the pump chamber 44 which is broadened at 95 its top 70 in order to connect with the pipe 16 and which is also broadened out at the bottom at 72 to connect with the pipe 20.

The operation and advantages of my invention will be apparent from the foregoing 95 description. The gears 46 and 48 serve as a pump to take water from the bottom of the radiator through the pipe 16 and force it through the pipe 20 to the engine from which it returns to the radiator through the 100 pipe 14. An efficient circulation of water for cooling the engine is thus provided. On account of the gear 48 being smaller than the gear 46 the fan will be driven much faster than the engine crank shaft and the cooling effect of the fan is therefore much increased. On account of the pivotal mounting of the pump casing the same may be readily adjusted by turning the lock nuts 36 for the purpose of tightening the sprocket chain or 105 whatever driving means is employed. On account of the location of the fan shaft upon

the casing on the side of the sprocket 54 toward the pivot, adjustment of the casing does not change the position of the fan relatively to the radiator sufficiently to have any effect on its efficient operation.

I claim:

1. In combination with an internal combustion engine and a radiator, a gear pump comprising two intermeshing gears of unequal size, means for driving the larger of said gears from the engine, a fan positioned in proximity to the radiator, and means for driving said fan from the smaller of said gears.
- 15 2. In combination with an internal combustion engine and a radiator, a pump casing, a pivotal mounting for said casing, a gear pump in said casing comprising two intermeshing gears, shafts to which said gears are respectively secured, flexible means for driving one of said shafts from the engine, a fan secured to the other of said shafts in proximity to the radiator, said fan shaft be-

ing located between said pivotal mounting and the other of said shafts, and means whereby said casing may be adjusted around said pivotal mounting to tighten said flexible driving means without disadvantageously changing the position of said fan.

3. In combination with an internal combustion engine and a radiator, a pump casing pivotally mounted on the front of the engine, a gear pump in said casing comprising two intermeshing gears of unequal size, shafts mounted in said casing to which said gears are respectively secured, driving connections between the shaft of the larger gear and the engine shaft, a fan secured to the shaft of the smaller gear in proximity to the radiator, a pipe leading from the radiator to said casing, a pipe leading from said casing to the engine, and a pipe leading from the engine to the radiator.

In testimony whereof I hereunto affix my signature.

GUY L. WILLITS.
